COMBINED CONDUCTOR JACK AND PLUG ASSEMBLY

Richard E. Brown, Gahanna, Ohio, assignor to
Twyco, Inc., Blacklick, Ohio

Filed Aug. 5, 1971, Ser. No. 169,592

Term of patent 14 years

Int. Cl. D13—03

U.S. Cl. D26—1 A

Fig. 1

Fig. 2

Fig. 3

FIG. 1 is a front perspective view of a combined conductor jack and plug assembly embodying my design.

FIG. 2 is a rear perspective view of the combined conductor jack and plug assembly.

FIG. 3 is a side elevational view of the combined conductor jack and plug assembly.

I claim:

The ornamental design for a combined jack and plug assembly, as shown.
